CLAIM

The ornamental design for a device for fixing satellite broadcast receiving antenna, as shown and described.

DESCRIPTION

FIG. 1 is a front elevational view of a device for fixing a satellite broadcast receiving antenna according to my new design, with the dashed lines showing a satellite broadcast receiving antenna and an antenna support, both of which do not form part of the present design but are shown for illustrative purposes only.

FIG. 2 is an enlarged rear elevational view of the device shown in FIG. 1.

FIG. 3 is a top plan view of the device shown in FIG. 2.

FIG. 4 is a bottom plan view of the device shown in FIG. 2.

FIG. 5 is a left side elevational view of the device shown in FIG. 2.

FIG. 6 is a right side elevational view of the device shown in FIG. 2.

FIG. 7 is a cross-sectional view of the device along a line 7—7 in FIG. 5; and,

FIG. 8 is a perspective view of the device shown in FIG. 2. The article is a device for fixing a satellite broadcast receiving antenna to an antenna support.
